POURING PRACTICE AND APPARATUS

William B. Arness, Baltimore, Md., assignor, by
mesne assignments, to Rustless Iron and Steel
Corporation, Baltimore, Md., a corporation of
Delaware

Application October 17, 1933, Serial No. 693,990

6 Claims. (Cl. 22—209)

This invention relates to the production of metal ingots, especially ingots of chromium alloy irons and steels, and to means and apparatus employed in the same.

5 One of the objects of my invention is the simple, economical and efficient production of metal ingots of relatively smooth surfaces, which are free of wrinkles, cracks, seams and scabs or cold shuts; which are likewise free of sub-cutaneous 5 non-metallic inclusions, blowholes and like defects; and which readily lend themselves to an efficiency and economy of rolling or otherwise working heretofore unknown.

10 Another object of my invention is the development of a simple, economical and thoroughly practical apparatus for pouring ingots of the character indicated, which is strong, rugged and of long life; which assures the production of 15 ingots of the character indicated with minimum cutting of the mold and localized ingot contamination from the mold metal and with maximum ease and economy in stripping mold from ingot.

15 Other objects in part will be obvious and in part pointed out hereinafter.

20 The invention, accordingly, consists in the combination of elements, features of construction and arrangement of parts, and in the several steps and the relation of each of same to one or more of the others, as described herein, the scope of 25 the application of which is indicated in the following claims.

In the accompanying drawing, illustrating certain features of my invention:

30 Figure 1 is a front elevation of a mold ready for teeming, with associated hot-top and pouring crucible, certain parts being broken away in order to more clearly illustrate certain features 35 of my invention.

35 Figure 2 is a plan view of mold, hot-top and pouring crucible shown in Figure 1.

40 Figure 3 is an end elevation of mold, hot-top and crucible shown in Figure 1 as seen from the right.

45 Figure 4 is a front elevation of an open-end ingot mold, of the big end up type with hot-top and pouring crucible operatively associated therewith all ready for teeming and

50 Figure 5 is a diagrammatic representation of metal rising in a mold where the supply stream is remote from the mold walls.

55 As conducive to a clearer understanding of certain features of my invention it may be noted at this point that in casting ingots, especially slab ingots of relatively large slab sections, of iron or steel and more especially alloy iron and steel,

a wrinkled, seamy unsound and cracked ingot surface ordinarily results. Particularly in the production of slab ingots of rustless irons and steels where a chromium content of from about 12% to 30% is employed, either with or without nickel in substantial amounts and supplementary additions of copper, cobalt, titanium, molybdenum, tungsten and the like as desired, the surfaces of the ingots, especially along the narrow sides, are wrinkled, cracked, seamy and unsound.

In, for example, top pouring a mold of comparatively large sectional area, or a mold where two or more of the walls are relatively remote from the center as in a slab mold where the end walls are 15, 20, 25 or more inches from the mold center, in accordance with heretofore known practice using conventional apparatus, a ladle of metal at a desired temperature is spotted over the mold and the teemed metal falls in a stream substantially axially of the mold. The molten metal flows from the center of the mold toward the end-walls and in doing so tends to cool at the surface and becomes thick, sluggish and sticky. This is particularly noticeable where the teemed metal is of high chromium content. Furthermore, during the teeming, non-metallic inclusions entering the mold tend to rise to the surface of the metal and form a sticky scum the amount of which is increased by atmospheric oxidation of the upper surface of the metal. This scum is carried with the surface flow of metal toward the end-walls of the mold where the turbulent effect of the metal is at a minimum. As surface metal and scum further cool a crust is formed which sticks to the metal freezing against the mold walls and forming the outer skin of the ingot.

Thus referring to A of Figure 5, metal 10 rising along the side wall 11a of mold 11 is covered by a sticky layer of scum or a plastic crust generally indicated at 12 which, for example, sticks at 10a to the skin 10b of the forming ingot. The rise of metal continues, as shown in B of Figure 5 and under the ferro-static pressure of the rising metal the scum or crust 12 breaks. The molten metal flows to the mold wall entrapping a section of scum or crust of non-metallic inclusions, generally indicated at 13, beneath the surface skin of the fast forming ingot.

The rising metal flows about the entrapped non-metallic inclusions indicated at 13 (see C of Figure 5) tending, in a measure, to reduce the included oxides with the consequent liberation of gas. The metal contacting the mold walls is

heavy, sticky and viscous and quickly solidifies thereby entrapping the gas bubbles causing blowholes beneath the skin of the ingot.

As the metal in the mold continues to rise substantially uniformly and with minimum disturbance near the remote end-walls, successive sections of the scum or crust covering the rising metal adjacent these walls stick to the upper part of the continuously forming ingot skin, break from the main body of scum or crust and become entrapped by the rising metal. The metal, then, in contact with the mold walls rises not uniformly and at a substantially constant rate but discontinuously producing thereby an uneven, wrinkled surface covered with cracks and fissures. Immediately beneath the wrinkled surface of the ingot are entrapped the various sections of non-metallic inclusions in the form of pieces of crust of various sizes together with entrapped gases, the whole forming an unsound and blowy sub-cutaneous layer.

In order to prepare the ingot for working into a desired intermediate form, such as a billet, bloom or slab suitable for finishing to sheet or plate, this wrinkled, seamy and cracked surface layer with sub-cutaneous oxide inclusions, blow-hole sections and the like must be completely removed down to clean, sound metal. The removal of this outer layer of defective metal is slow, costly and inefficient.

It may be further noted at this point that in teeming ingots in accordance with heretofore known methods and pouring equipment, that in order to partially avoid the many defective ingot surface and sub-surface conditions a number of which are referred to above, the metal is poured into the mold in a large stream and at an excessive rate. Fast pouring, even when the metal is relatively "cold", induces longitudinal surface cracks as well as spots, scabs or cold shuts caused by metal splashed against the mold walls where the splashings immediately freeze and subsequently become incorporated in the skin of the ingot (ordinarily the metal contacting the mold walls is not sufficiently hot to melt these splashings).

Furthermore in pouring the metal in a large stream, the edges of the stream may be as near as two or three inches of the side-walls of a mold. Such a stream under a high ferro-static pressure (even where this pressure is reduced and the stream accurately controlled by a pouring crucible between ladle and mold) causes an excessive wash of metal against the bottom and side-walls of the mold, cutting into the mold bottom and walls, decreasing the normal mold life, contaminating the fast forming skin of the ingot in localized areas with the high carbon cast iron of the mold and causing the ingot to stick in spots to the walls of the mold. The subsequent stripping of the ingot is slow and unduly difficult. The stripped ingot has a torn and scabby bottom, is objectionably contaminated with mold metal in sections adjacent the bottom and is inclined to have surface checks and cracks in addition to the many faults indicated above.

One of the objects of my invention is the production in a simple, economical and reliable manner with a minimum of expensive and/or complex equipment, of smooth even surface ingots, free of seams, wrinkles and cracks; free of scabs, cold shuts and the like; free of sub-cutaneous non-metallic inclusions, gas pockets and pits; and free

of objectionable localized contamination of the ingot mold.

In the practice of my invention in casting a slab ingot of rustless iron, for example, employing a slab mold having wide side-walls and narrow end-walls, the side-walls being relatively near the major lateral axis of the mold and the narrow-end walls being comparatively remote from the mold center, molten metal is poured into the mold in a plurality of spaced streams of reduced size. Each stream is maintained near the walls of the mold in order to assure a desired turbulence of metal washing the various walls of the mold and precluding the formation of a definite scum and subsequent crust of non-metallics on the surface of the rising metal, and to furthermore prevent the sticking of such a crust to the forming ingot or to the mold walls to be subsequently entrapped in the skin of the ingot as more particularly described above, to form the wrinkled outer surface and the many sub-surface defects indicated. The turbulence of metal is not so great, however, as to cause a cutting of the mold bottom and walls with the many attendant injuries to mold and ingot a number of which are set forth above.

Thus, referring to the accompanying drawing and more particularly to Figures 1, 2, and 3, an ingot mold 15, of cast iron, illustratively of the Gathmann type, having an open top portion, indicated at 15a, and a closed bottom portion 15b (see Figure 1) is set up in a vertical position, handling of the mold being achieved by staple 16 embedded in the side-walls of the mold, on blocks 17 resting on a pit bottom generally indicated at 18. Mold 15 (see Figure 2) has opposite wide side-walls 15c and 15d spaced relatively near the center of the mold and narrow side-walls 15e and 15f spaced remotely from the mold center. The inner walls of the mold are tapered sufficiently to permit easy stripping of the fully formed ingot from the mold.

In teeming, a ladle (not shown) is suspended above the mold at a suitable height with the ladle nozzle substantially axial of the mold. By control of the ladle nozzle opening, metal is permitted to flow into the mold.

In order to reduce the ferro-static pressure of the teemed metal, especially during the initial periods of teeming when the mold is empty and the tendency of splash is at a maximum, and to achieve a desired turbulent effect of metal in the mold, thereby assuring a continuous wash of metal along the various mold walls, a pouring crucible or pot 19, comprising a basin 19a (see Figure 1) and outwardly extending nozzles illustratively 19b and 19c, is interposed between mold and ladle. Chilling and freezing of the metal in the pouring crucible is effectively prevented by employing a crucible pre-heated to approximately 1800° F. This pre-heating is carried out in any convenient manner, as by means of a gas-fired oven. A number of crucibles are kept hot in the oven and are withdrawn for use in a pre-heated condition as indicated above.

The pouring crucible 19 is conveniently mounted upon the horizontal supporting bars 20 (see Figure 2) which rest upon the upper edge 70 of a hot-top 21. In accordance with standard pouring practice, hot-top 21 loosely fits within the open-end portion 15a of mold 15 where it is conveniently supported by bricks 22 engaging the projecting lugs 21a of the hot-top.

Crucible 19, preferably made of graphite bonded with fire-clay in order that it may withstand the necessary pre-heating, wash of metal and the high temperatures encountered, is of elongated section similar to the section of the mold with which it is used. Preferably, (see Figure 1) basin 19a and nozzles 19b and 19c are individually fashioned in order that the nozzles after being excessively worn by the wash of teemed metal, or possibly frozen over with cold metal, may be readily replaced thus prolonging the life of the crucible.

Nozzles 19b and 19c extending outwardly from the basin of the crucible are spaced at opposite ends of the bottom of the basin at such a distance that each of the nozzles, when the crucible is in use, is at a permissible distance from the mold walls or is substantially equidistant from three of the walls of the mold.

Thus referring more particularly to Figure 2, crucible 19 maintained in substantial axial alignment with mold 15 (see also Figure 1) with nozzles 19b and 19c in substantial alignment with the major lateral axis of the mold, has the pouring nozzles so spaced that the nozzle 19b is relatively near and substantially equidistant from mold walls 15c, 15d, and 15f and nozzle 19c is likewise near and substantially equidistant from the mold walls 15c, 15d, and 15e.

Metal flowing into crucible 19 in a central stream from the ladle flows out of the crucible by way of nozzles 19b and 19c in two streams adjacent the side walls of the mold at a uniform, even rate. The falling streams of metal assure a turbulent condition in the mold and a wash of metal along the mold walls to prevent the formation, sticking and entrapping of a non-metallic scum or crust, thus assuring the production in a simple, inexpensive and thoroughly reliable manner, of an ingot of substantially smooth, continuous surface with a minimum of localized skin contamination with mold metal and a minimum of sub-cutaneous non-metallic inclusions, blowholes and the like. A substantially uniform wash of metal along the walls of the mold is assured by spacing the streams of metal apart a distance approximately double the distance to the nearby mold walls, each stream of metal then maintaining a desired wash along the side-walls of the mold throughout substantially equal angles toward and away from the other stream. Thus, referring to Figure 2, nozzles 19b and 19c of the crucible are spaced from each other a distance approximately twice that of the nozzles to the nearby mold walls 15c, 15d and 15f and 15c, 15d and 15e respectively, when the crucible is properly positioned over the mold, as more particularly described above. This construction assures a comparatively uniform and vigorous wash of metal against the mold side-walls 15c and 15d throughout the extent of these walls.

After teeming, crucible 19 is moved to the next ingot mold where it is conveniently positioned on the hot-top associated with this mold. Bricks 22 supporting hot-top 21 are removed so as to permit the movement of the hot-top further into the mold incident to the normal shrinkage of the cooling ingot.

During the initial pouring period when the mold is empty, the direct impact and wash of hot metal tends to cut into the mold bottom and so limit the life of the mold to a comparatively few times used. In order to assure maximum mold life the bottom portion 15b of the mold is

formed with tapering holes 15g and 15h (see Figure 1) in substantial alignment with the major lateral axis of the mold and spaced equidistant on opposite sides of the longitudinal axis of the mold a distance corresponding substantially to the spacing of the nozzles in the pouring crucible. Thus, referring to Figure 1, holes 15g and 15h respectively are in substantially direct alignment with nozzles 19b and 19c of the pouring crucible operatively associated with the 10 mold.

The mold bottom is completed by cast iron plugs 23 and 24 respectively interfitting the tapered holes 15g and 15h. These plugs are sufficiently large to catch the direct impact of the streams of metal initially falling into the empty mold during teeming and are sufficiently long (see Figures 1 and 3) as to extend beyond the outer bottom surface of the ingot mold, as indicated at 23a and 24a respectively, so as to facilitate the stripping of the ingot. As plugs 23 and 24 become worn as a result of the wash of metal upon their upper surfaces during the initial periods of teeming many heats of metal these plugs are replaced by new plugs, thus simply and economically prolonging the life of the mold.

In addition to minimizing metal splash by employing a plurality of smaller streams of metal in teeming, and the accompanying decrease in scabs and cold shuts as well as the amount of sticking of ingot to mold, the splash of metal impacting the bottom of the empty mold is further minimized by the mold bottom design wherein curved wall sections, 15k, 15m, 15n, 15p join bottom wall 15b with the respective side and end walls 15c, 15d, and 15e, 15f (see Figures 1 and 3). The streams of metal in striking the upper surfaces of plugs 23 and 24 spread and by means of the concavely curved wall sections are deflected back toward the mold center with a minimum of splash upon the straight side and end walls of the mold thus assuring a smooth ingot butt free of scabs or cold shuts and with a minimum of sticking of ingot to the mold bottom.

Where a slab mold of the open-end type (see Figure 4) is employed, excellent results in casting an ingot of smooth surface and comparatively free of sub-cutaneous defects is achieved by interposing between mold and ladle a pouring crucible having a plurality of nozzles spaced to assure the maintenance of streams of metal falling into the mold sufficiently near the mold walls to maintain a turbulent condition of the metal with the consequent prevention of a wrinkled seamy or cracked ingot surface and the entrapping of sections of non-metallics and gas inclusions, all as more particularly described above.

Open-end mold 25 of the big end up type, is mounted upon a stool 26 having embedded therein a cast iron stool insert 27. In teeming, a pouring crucible or pot 28 having a plurality of crucible nozzles 28b and 28c is conveniently supported by bars resting upon the upper edges of hot-top 29 conveniently mounted upon the top of the mold. Crucible or pot 28 is designed with respect to 25 so that the pot nozzles direct streams of molten metal adjacent the mold walls in order to maintain a turbulence of metal washing the walls and assure the production of smooth surface ingots free of subcutaneous non-metallic inclusions and blowholes, all as more particularly described above. The utilization of a plurality of streams in filling the mold in a measure prevents the 10-75

calized cutting away of the insert, as with a single stream of increased size, and in addition measurably decreases the amount of splash encountered with a single large stream of metal, thus 5 permitting the production of an ingot having a minimum of scabs or cold shuts and the realization of maximum mold life.

Thus it will be seen that there has been provided in this invention a method and apparatus 10 for economically and efficiently teeming ingots, in which the various objects hereinbefore noted together with many thoroughly practical advantages are successfully achieved.

While in the embodiment of my invention illustratively described above a slab mold having two bottom plugs and an associated pouring crucible having two nozzles are described it will be understood that three, four or more pouring nozzles spaced along the axis of the pouring crucible 20 may be employed when desired and a mold of great width as compared to thickness may be used therewith, the mold bottom plugs preferably corresponding in number and in location to the nozzles of the associated pouring crucible.

25 Likewise, in teeming a mold of large cross section having substantially equal sides, it will be understood that many practical advantages may be achieved by employing a pouring crucible operatively associated therewith wherein a plurality of crucible nozzles are used, spaced adjacent the projected walls of the mold, in order to assure a desired wash of metal along the mold walls and to achieve a desired smooth surface 30 ingot free of sub-cutaneous defects.

35 As many possible embodiments may be made of my invention and as many changes may be made in the embodiments hereinbefore set forth, it is to be understood that all matter described herein, or shown in the accompanying drawing, 40 is to be interpreted as illustrative, and not in a limiting sense.

I claim:

45 1. In the production of high chromium alloy iron and steel slab ingots, the art which includes, pouring molten high chromium alloy iron or steel into a slab mold a plurality of streams substantially evenly spaced along the major axis of the mold and maintained uniformly adjacent the side-walls and end-walls thereof, thereby 50 creating a regular wash of metal against the walls of the mold and preventing the formation and entrapment of non-metallic inclusions in the forming ingot, whereby an ingot free of sub-cutaneous blowholes, oxide inclusions and the like is effectively achieved.

55 2. In the production of rustless iron ingots in a slab mold, the art which includes, pouring molten rustless iron into said mold in two streams evenly spaced opposite side walls and end-walls of the mold, thereby creating a uniform wash of metal along the walls of said mold and preventing the entrapment of a surface crust of non-metallic inclusions beneath 60 the skin of the forming ingot, whereby an ingot free of sub-cutaneous defects is effectively achieved.

3. In the production of high chromium alloy iron and steel ingots in a slab mold, the art which includes, maintaining above said mold and in substantial alignment therewith a pouring crucible having a pair of nozzles therein each of which is so spaced as to lie adjacent the projected walls of the mold and substantially equidistant opposite side-walls and an end-wall thereof, and pouring molten high chromium alloy iron or steel into said crucible, thereby forming two streams of metal each of which falls adjacent the end-walls and adjoining side-walls of said mold and creating a turbulence of metal uniformly washing the walls of the mold whereby ingots free of sub-cutaneous defects are produced.

4. In the production of metal ingots of greater width than thickness, in combination, a slab mold having a plurality of hole portions spaced along the major axis of the bottom thereof, the extreme hole portions being substantially equidistant from an end-wall and opposite side-walls of the mold, a corresponding plurality of plugs interfitting the hole portions of the bottom of said mold, a pouring crucible having a plurality of nozzles so spaced as to correspond in number and arrangement with the hole portions of the bottom of said mold, and means supporting said crucible so as to space the nozzles thereof in substantial alignment with the plugs in interfitting the hole portions of said mold bottom and substantially equidistant from the side-walls of said mold, whereby metal poured into said crucible falls in a plurality of streams initially striking the plugs interfitting the hole 35 portions of the mold bottom and then deflecting against the walls of said mold and from the outset creating a turbulence of metal washing the mold walls and assuring the production of ingots free of sub-cutaneous defects.

40 5. In the production of metal slab ingots, a pouring crucible comprising in combination, a refractory basin of elongated rectangular section, and a plurality of outward extending nozzles spaced along the major axis of said basin at 45 intervals substantially equal to twice the spacing of the extreme nozzles from opposite side-walls and an end-wall of the basin.

50 6. In the production of high chromium alloy iron and steel slab ingots, a slab mold comprising in combination, a bottom portion having wide side-wall and narrow end-wall portions rising therefrom, said bottom portion having a plurality of openings therein spaced along the major axis thereof at intervals substantially double the spacing between the extreme openings and the adjoining end-wall and side-wall portions of the mold, and plugs interfitting said openings whereby molten high chromium iron and steel poured into said mold in a plurality 60 of streams corresponding in number and spacing to said plugs initially impinges upon said plugs creating a uniform wash of mold wall portions and assuring the production of slab ingots free of sub-cutaneous defects.

65

WILLIAM B. ARNESS.
